J. M. Adams,

Crimping Leather

No 84,402.

Patented Nov 24, 1868.

United States Patent Office.

OLIVER M. ADAMS, OF MILFORD, MASSACHUSETTS.

Letters Patent No. 84,402, dated November 24, 1868.

IMPROVEMENT IN BOOT-CRIMPERS.

The Schedule referred to in these Letters Patent and making part of the same.

To all whom it may concern:

Be it known that I, OLIVER M. ADAMS, of Milford, in the county of Worcester, and in the State of Massachusetts, have invented certain new and useful Improvement in Boot-Crimpers; and I do hereby declare that the following is a full, clear, and exact description thereof, reference being had to the accompanying drawings, and to the letters of reference marked thereon, in which—

Figure 1 is a side elevation.

Figure 2 is a longitudinal section.

Figure 3 is a section of one of the movable jaws.

Figure 4 is a top view of the movable plate.

The nature of my invention consists in the improved face of the sliding jaws, and in the manner of operating said jaws, as will be hereinafter fully described.

To enable others skilled in the art to make and use my invention, I will proceed to describe its construction and operation.

In the construction of my invention, I use the clamp or fulcrum *a*, and screw *c*, and screw-nut *d*, such as are in common use in boot-crimps of this class.

I cut a slot through the top of the clamp or fulcrum *a*, to suit the size of the screw, and entirely across the space between its angles. I then construct my jaws, *b b*, the width of the sides of clamp *a*, and about an inch long. To this jaw an arm extends up about one and a half inch, making the entire length of the jaw about three inches. On each side, near the top, is cut a groove, an eighth of an inch in depth and width, as seen in fig. 3. The inner side of these jaws, from about half way up, descends from a straight line outward, forming an obtuse angle, thus leaving the space between them wider at the lower end than at the middle. The faces of these jaws are cut in rows of teeth, which are segments of rows, in straight lines, at right angles across the faces of the jaws, as seen at fig. 3, to give greater power in holding the leather than when the teeth are in lines entirely across the face of the jaws, as heretofore.

By making the teeth or clamping-lines serrated or in segments, the open spaces and the solid cross-lines, alternating, give to the jaws a much firmer hold, as the leather is compressed or indented between the teeth in different directions, and making them less

liable to slip. I regard this a great improvement in boot-crimps.

I may find it convenient to make the rows of teeth in diagonal lines to each other, in quarter sections, on the face of the jaw, in segments.

The plate *d* is slotted, as seen in fig. 4, and the upper end of the jaws *b b* passes up through it, and the grooves are made to fit in the plate, so that, as the plate moves up or down, the jaws move with it.

The screw *c* is made to pass through the plate *d* and fulcrum or clamp *a*, and, after it is thus inserted, the screw-nut *e* is screwed on it, as seen in figs. 1 and 2. This nut is tapered on its four sides, to correspond with the inclination given to the jaws *b b*.

The machine thus arranged is ready for operation.

In its operation, the leather to be crimped is fitted to the tree, and the screw *c* turned up until its end will rest on the back edge of the boot-tree, and the clamp and jaws descend far enough to take hold of the leather between the jaws and clamp, when the screw *c* is then turned, bringing the nut *e* up between the jaws, pressing them tightly in on the leather, and gripping firmly, by the teeth, on its surface, making alternations on the face or gripe, not so liable to slip as if the edge of the teeth passed entirely across the face of the jaw. As the screw is turned, the clamp and jaws are carried up, causing the leather to be drawn with them, thus crimping the same, and giving it the required crimp or shape required in a boot-leg, to fit the instep.

Having thus described the construction and operation of my invention,

What I claim as new, and desire to secure by Letters Patent, is—

The jaws *b b*, with serrated or segmental rows of teeth, in straight lines, at right angles to the jaws, as described, and in combination with plate *d*, and clamp *a*, screw *c*, and screw-nut *e*, constructed and operating as and for the purposes set forth.

In testimony that I claim the above-described invention, I have hereunto signed my name, this 21st day of February, 1868.

OLIVER M. ADAMS.
